UNITED STATES PATENT OFFICE.

ANTHONY G. SALERNO, OF CHICAGO, ILLINOIS.

COLLAR.

1,375,182.

Specification of Letters Patent. Patented Apr. 19, 1921.

Application filed September 2, 1920. Serial No. 407,763.

To all whom it may concern:

Be it known that I, ANTHONY G. SALERNO, a citizen of the United States, residing at Chicago, in the county of Cook and State 5 of Illinois, have invented certain new and useful Improvements in Collars, of which the following is a specification.

My invention relates to detachable "soft" or unstarched collars designed to be attached to a shirt as an article of wearing apparel. While comfortable, sanitary, and desirable, collars of this character easily become wrinkled and crumpled, and it is the object of my invention to provide a soft collar 10 formed and adapted to receive as a liner an ordinary stiff or starched collar of corresponding shape—or, if desired, a foldable liner of similar shape and of any other suitable material—to prevent the soft collar from wrinkling and cause it to keep the shape and present a neat appearance, thus adding to the comfort of the wearer and enabling the collar to be worn a longer time. Another object of my invention is to provide 15 a collar which, when formed of woolen or other warm fabric, will serve in cold weather to keep the neck warm and serve as a substitute for a muffler. To the ends in view, and to attain the objects mentioned 20 and other incidental objects and advantages which will be apparent from the description hereinafter given, I have invented and designed the novel soft collar and liner structure illustrated in the accompanying 25 drawings and which will now be described, the essential elements of my invention being more particularly pointed out in the appended claims, it being understood, however, that modification of the form and construction of the parts is possible without departing from the scope of the claims or the spirit of the invention, and that I do not intend to limit my invention to the 30 specific form or details of construction of 35 the structure described.

Figure 1 of the accompanying drawing is a plan view of the inner side of a portion of a soft collar and its lining member embodying a preferred form of my invention, 40 slightly more than one-half of the collar being illustrated, and the members being shown unfolded and opened out flat and broken away in places to better show the relation of the parts; Figs. 2 and 3 are similar views respectively illustrating two other

and different modified forms of my invention; Figs. 4, 5 and 6 are, respectively, transverse sections of the collars shown in Figs. 1, 2 and 3, taken through the center of the folded collars; Fig. 7 is a perspective of a 60 complete collar in folded position; and Figs. 8, 9 and 10 are complete plan views of the collars shown in Figs. 1, 2 and 3, respectively.

The same letters of reference indicate the 65 same parts in all the figures of the drawing.

Describing first the preferred form of my invention illustrated in Figs. 1, 4 and 8 of the drawing, my improved collar comprises a soft collar member of any desired pliable 70 fabric supported upon a separable stiff lining member of any suitable and desired pattern such as the conventional shape illustrated. The outer member, or soft collar proper, consists of an outer ply 1, and an 75 inner ply 2, extending over the flap portion of the outer ply and the end portions of the neck-band part thereof, the plies being secured together along their meeting edges, thus leaving an opening 3 extending over 80 the center of the neck-band portion of the article and terminating short of the ends thereof. The neck-band portion of the outer ply is formed with a button hole 4 adapted to register with the central or rear 85 button hole 4^a of the stiff collar lining member 5, and the plies 1 and 2 are both formed with button holes 6 arranged to register with front button hole of the stiff collar. In the drawings the dotted line 5^a indicates 90 the margin of the lining member 5 (other dotted lines indicating lines of stitching), and the folding lines between the flap and neck-band portions of the members are indicated by a plurality of light full lines. 95 It is obvious that the stiff collar may readily be inserted in the soft collar member through the opening 3 when the collar members are unfolded or opened out in flat form, and the two members may then be 100 folded together to form a collar which in appearance resembles a soft collar (see Fig. 7), but which, when applied to a shirt by means of the collar buttons passing through the registering button holes, will retain its 105 shape and present a neat appearance until it becomes soiled from wear. A single stiff collar will serve as a liner for any number of soft collars of the same pattern, which thus makes my new collar particularly suit- 110

able for traveling, since a large number of soft collars may be packed so as to occupy but little space.

The modified form of my collar shown in Figs. 2, 5 and 9 differs from the preferred form above described in that the rear or inner ply marked 2^a, extends over both the flap and neck-band portions of the article, and is secured to the outer ply around its entire margin, a transverse central slot 7 being provided for insertion of the lining member.

In the modification shown in Figs. 3, 6 and 10 the inner ply 2^b extends over both the flap and neck-band portions of the collar, as in the construction shown in Fig. 2, but the outer and inner plies are left unstitched and disconnected from each other along the central portion of the margin of the neck-band of the collar, thus leaving an opening for insertion of the lining member.

I claim:

1. A collar comprising separable similarly shaped outer and lining members each having neck-band and flap portions, said outer member being formed of pliable fabric and having outer and inner plies connected at the meeting margin of the flap portions and of the ends of the neck-band portions and there being an opening between said plies intermediate the ends of the members, and said lining member being relatively stiff and

foldable together with said outer member along a line between the neck-band and flap portions of the members.

35

2. A collar comprising separable similarly shaped outer and lining members each having neck-band and flap portions, said outer member being formed of pliable fabric and having outer and inner plies connected at the meeting margin of the flap portions and of the ends of the neck-band portions and said plies being free from each other along the central portion of said members, and said lining member being relatively stiff and foldable together with said outer member along a line between the neck-band and flap portions of the members.

40

3. A collar comprising separable similarly shaped outer and lining members each having neck-band and flap portions, said outer member being formed of pliable fabric and having outer and inner plies connected at the meeting margin of the flap portions and of the ends of the neck-band portions and said neck-band portion of the inner ply being cut away to form a longitudinal opening along the center portion of said outer member, and said lining member being relatively stiff and foldable together with said outer member along a line between the neck-band and flap portions of the members.
